UNITED STATES PATENT OFFICE

144,412

DESIGN FOR A FLAG

Chesley R. Perry, Chicago, Ill.

Application May 26, 1945, Serial No. 119,752

Term of patent 3½ years

(Cl. D29—17)

To all whom it may concern:

Be it known that I, Chesley R. Perry, citizen of the United States, residing at Chicago, in the County of Cook and State of Illinois, have invented a new, original, and ornamental Design for a Flag, of which the following is a specification, reference being had to the accompanying drawing, forming part thereof.

The figure is an elevational view of a flag showing my new design.

I claim:

The ornamental design for flag, substantially as shown.

CHESLEY R. PERRY.
